REVERSIBLE WINDOW CONSTRUCTION

Wendell B. Tidwell, Norfolk, Va., assignor to Window-Frame Corporation, Norfolk, Va., a corporation of Virginia

Application June 11, 1947, Serial No. 753,986

8 Claims. (Cl. 20—52.2)

1

The present invention relates to improvements in the construction of windows of the type used principally for residences and offices, and is directed particularly to a reversible window construction which is useful for both indirect ventilating and convenient cleaning.

A principal object of this invention is to provide an improved window construction applicable to either wood or metal fabrication in which a sash carrying frame is supported for bodily movement out of a fixed window frame forming a part of the building construction.

A more specific object of the invention is to be found in the provision for unobstructed movement of a conventional pair of vertically sliding sash in any position of the movable assembly.

A further and important object of the invention resides in the provision of a novel window construction in which the sash carrying frame can be moved to a position of spaced relation from the fixed window frame when indirect ventilation is desirable or necessary.

An additional principal object of the invention is to provide a window construction in which the sash may be quickly and easily reversed for safe cleaning or repair within the building. Specific features of improvement incidental to this object include provision for reversal of the window sash without removal of any of the parts of the window construction or disconnection of conventional sash balances.

Further specific objects of this invention reside in the provision for the conventional use of window screening and storm windows, adequate sealing of the movable window sash assembly in the fixed window frame, and preservation of an architecturally acceptable window appearance both from within and without.

A further specific object is to provide a window construction in which the sash may be reversed for convenience and safe cleaning without causing undue leakage of outside air into the building.

These and other features of improvement contributing to complete satisfaction in use and economy of manufacture will be apparent from the following detailed description of a preferred embodiment taken in connection with the accompanying drawings in which:

Fig. 1 is a partially sectioned inside elevation of the assembled window construction in normal relation;

Fig. 2 is a vertical section taken on line II—II of Fig. 1 showing the assembled window construction to an enlarged scale;

Fig. 3 is a horizontal enlarged section taken on

2

line III—III of Fig. 1 and showing the window components in a different operative relation;

Fig. 4 is a side elevation partly in section of the window construction in the operative relation of Fig. 3;

Fig. 5 is a cross-sectional view taken on line V—V of Fig. 2;

Fig. 6 shows an inside elevational view of the assembled window with certain parts removed for purposes of illustration;

Fig. 7 is a vertical section to reduced scale taken on line VII—VII of Fig. 4 with certain parts in a different adjusted position;

Fig. 8 is a partial cross-sectional view to an enlarged scale taken on line VIII—VIII of Fig. 1; and

Fig. 9 is a fragmentary inside elevational view partially sectioned showing a bottom portion of the movable window frame assembly.

As seen best in Figs. 3 and 4, the window construction of this invention comprises a window wall frame 10 to be fixed in a corresponding opening in a house or other building, and a bodily movable and reversible window sash assembly 12 connected with the wall frame 10 by upper and lower linkages 14 and 16. The relation of the frame 10 to the opening in the house or other building is shown by dotted wall lines WL.

The fixed window frame 10 comprises an upper horizontal member or lintel 18 and a lower horizontal member or sill 20 secured at their ends to a pair of vertical uprights or framing members 22 and 24. A rectangular outer facing frame 26 covers the outer edges of wall frame 10 and overlaps the adjacent margins of the building structure in which it is mounted. Adjacent its lower portion and immediately above the sill 20, the facing frame 26 is provided with a drain ledge 28 extending the full width as shown in Fig. 3.

The drain ledge or strip 28 is formed with a convex inner edge 29, extending throughout the widthwise opening provided by said frame, for sealing purposes which will be more fully described. An inner mold strip 30 of rectangular cross section extends interiorly around the other three side edges of the facing frame 26 in the manner shown in Figs. 2, 4 and 7 to serve as a guide and seal for the movable sash assembly 12.

With reference to Figs. 2, 3 and 4, it will be observed that the window sash assembly 12 which is mounted for bodily movement includes upper and lower framed sashes 32 and 34 guided for vertical movement by parallel side jambs 36, 36 having respective side facing members 37 se-

cured thereto and extending laterally to cover the inner edges of the members 22 and 24 of the fixed wall frame 10. The jambs 36 are connected at their upper ends to an overhead lintel 38 and at their lower ends to a sill member 39 of special shape. The sill member 39 is formed to provide a central inwardly inclined portion 40 terminating in a concave edge 41 formed and arranged for complementary engagement with the convex inner edge 29 of the drain ledge 28 as shown best 10 in Fig. 2. The size and slope of the inclined or wedge portion 40 is such as to fill snugly the wedge-shaped opening of the facing frame 26 adjacent the sill edge 29. The remaining inner portions of the sill 39 adjacent the respective ends of the wedge portion 40 will engage and abut the corresponding portions of the inside of the outer frame 26 as indicated in Figs. 3 and 7.

Figs. 2 and 8 best show the manner in which the overhead lintel 38 and the side jambs 36 engage the adjacent side of the inner mold strip 30 when the window sash assembly 12 is received in the frame 10. The sash 32 and 34 are of conventional construction and arrangement for sliding between a vertical parting strip 42 and inner and outer stop strips 44 and 46 disposed as shown in Fig. 8. A conventional ledge member 47 is secured to the inner marginal portion of the sill 39 so as to provide further guiding and abutment for the lower sash 34. The side facing members 37, 37 extend between and abut the inward projections of overhead lintel 38 and the sill member 39.

Figs. 1 and 4 illustrate the manner in which conventional forms of sash balance may be associated with the sash 32 and 34. In the preferred embodiment, these sash balances comprise weights 48, 48 arranged on opposite sides of each sash and connected with respective cords 50 extending over pulleys 52, 52 to engage respectively 40 with the balanced sashes 32 and 34.

The details of the upper and lower sash linkages 14 and 16 will be understood from a consideration of Fig. 3. The linkage 14 has a pivot pin connection 54 with a hinge plate 56 located at its inner end and secured to the upper horizontal framing member 18 by means such as a plurality of screw threaded fasteners 58, 58. The framing member 18 is provided with a recess 60 at its inner right end formed and arranged to receive the linkage 14 in its collapsed or folded position. At its outer end the linkage 14 has a similar pivot pin connection 62 with a hinge plate 64 secured by screw threaded fasteners 66, 66 to the central portion of the inner face of a pivotally mounted upper trim 68. The upper trim 68 is mounted for pivoting on the sash frame lintel 38 and a corresponding pivotally mounted lower trim 70 is carried on the underside of the sash frame sill 39, the pivotal axes being central and aligned vertically.

Further details of the pivotal association of the trim members 68 and 70 with the sash frame are shown in Fig. 9 which illustrates the mounting of trim 70, it being understood that the inverted mounting of the upper trim 68 is the same. A headed pivot pin 72 is threaded secured in the trim 70 and extends loosely through a securing and bearing plate 74 which is inset in the underside of the sill 39 and secured in place by 70 countersunk screws 76, 76. The sill member 39 is also recessed at 78 to provide clearance for rotation of the headed pin 72 with the lower trim 70. Pivot pin 72 is secured against rotation in trim 70 and turns loosely in the bearing plate 74.

As the construction and arrangement of the linkage 16 is similar except for its location on the bottom and at the opposite side of the sash assembly 12, it will suffice to note that an inner pivot pin connection 80 joins the linkage to a hinge plate 56, an outer pivot pin connection 82 is associated with hinge plate 64, and the upper inner edge portion of the framing sill 20 is recessed at 84 (Fig. 4) to receive the linkage. Each separate linkage means, 14 or 16, is of a length sufficient for reversing of the sash assembly 12 in its inner pivoting position.

The upper linkage 14 comprises a long link 86 pivotally connected to a short link 88 disposed adjacent the trim 68. A leaf spring 90 is secured to one side of the long link 86 and formed and arranged to extend over the connection between the two links and an adjacent edge of the short link 88 to provide a yielding stop against straightening of the toggle connection of the linkage and folding of the linkage in the opposite direction from that shown in Figs. 3 and 5. The manner in which the spring 90 cooperates with the links 86 and 88 when the bodily movable window sash assembly is completely withdrawn from the fixed frame 10 is clearly shown in Fig. 3.

Figs. 2 and 5 show the preferred manner of holding or locking the movable sash assembly 12 within the fixed frame 10 for use in a conventional manner. For this purpose, individual bolts 92 are arranged to extend outwardly through the overhead lintel 38 and the sill 39, respectively, for threaded engagement with nut members 94 countersunk and retained in the upper framing member 18 and the lower framing member 20 of the fixed frame 10. Each bolt 92 is provided with a butterfly head 96, which is countersunk in the inner face of the overhead lintel 38 or the sill 39 as the case may be when the threaded ends of the bolts are tightened into the nuts 94. The head 96 of the lower bolt 92 is covered by the bottom of the sash 34 when the latter is in a closed position, and the head 96 of the corresponding upper bolt 92 comes between the parting and stop strips where it will be inconspicuous. It will be appreciated that these bolts are readily accessible from the inside of the window and that they cannot be tampered with or released when the upper and lower sash are closed and locked in the usual manner. Fig. 5 shows the manner in which the bolts 92 are arranged to pass through the sash linkages when the latter are in closed position.

In order to secure and steady the bodily movable window sash assembly 12 in its spaced position within the house or other building (Fig. 4), detachable strut means in the form of metal gate hooks 98, 98 may be pivotally connected to the inner sides of the vertical framing members 22 and 24 adjacent the bottom and engaged with eyes 99, 99 secured to the inside faces of the vertical facing members 37 of the movable sash frame. The fixed framing members 22 and 24 also carry retaining pins 100 for holding the gate hooks 98 in vertical position when not in use, as illustrated in Fig. 7.

The usefulness and versatility of the window construction of this invention will appear more fully from the following description of its operation and use. When the movable window sash assembly 12 is secured within the fixed frame 10 as shown in Fig. 2, the individual sashes 32 and 34 may be slid up and down in the usual manner. The movable assembly 12 is unsecured by loosening and withdrawing the upper bolt 92 by means

of the inwardly exposed head 96, and the lower bolt 92 may be removed in the same manner after the lower sash 34 has been raised sufficiently to provide access to the bolt head 96. This unsecuring is quickly and readily accomplished from the inside of the building with which the window is associated. A straight inward pull on the window sash assembly 12 will move it bodily out of the fixed frame 10 and unfold the upper and lower linkages 14 and 16 which suspend it from the fixed frame 10. This position of operation is shown in Fig. 3 after the hooks 98 have been connected with the eyes 99 on the inside of the facing members 37 of the movable sash frame. In this position indirect ventilation of the interior of the building is provided around the whole inside periphery of the fixed frame 10. It will be particularly observed that no part of the window construction required adjusting or moving in this operation, except for separation of the securing bolts 92. The sash weights 48 and cords 50 are now exposed for convenient adjustment and repair, although conveniently removable boxing in sides can be provided if desired.

When the hooks 98 are unfastened the vertically aligned central, pivotal connections provided by pins 12, 72 permit the window sash assembly 12 to be rotated through a half turn or 180 degrees from the position shown in Fig. 3. This turning places the side facing members 37 adjacent the inner edges of the upright framing members 22 and 24 against which they may be pushed in order to close the opening of frame 10 while the insides of the sash 32 and 34 are being washed, repaired or painted. The pivotally mounted upper and lower trims 68 and 70 to which the pivot pins 72, 72 and the linkages 14 and 16 are connected will remain facing in the same direction in order to accommodate this half turning of the remainder of the window sash assembly and inward movement with the linkages to seal the upper and lower edges of the opening defined on the inner side of the fixed frame 10.

In addition to the complete sealing provided by the inner mold strip 30 and interfitting of the wedge-shaped sill portion 40 with the drain ledge 28 of frame 19, weatherstrips may be added around the outside edge of side jamb 36 and the window assembly lintel 38.

It will thus be seen that the objects of this invention have been attained by providing an attractive window construction having a window sash assembly which may be moved inwardly for purposes of indirect ventilation and reversed for convenient and safe access to the outer sides of the window sash without appreciable leakage of air into the room during the operation. These objects have been accomplished without materially increasing the cost of the window construction or material departure from conventional features, and without requiring the separation of any of the window parts during operation.

While a preferred embodiment of this invention has been described in detail, it will be appreciated by those skilled in the art that various changes can be made in details of construction and arrangement of parts without departing from the principles of the invention and the scope of the appended claims.

Having thus described my invention what I claim as novel and desire to secure by Letters Patent of the United States is:

1. A reversible window construction comprising a frame adapted to be fixed in a window opening of a building; a window assembly with

two vertically movable sashes and having lintel, sill and side jambs fitting within said frame in sliding relation; and separate linkage means pivotally connected to said frame at respective inner portions and with said lintel and sill respectively at points on a common central vertical axis, said separate linkage means each being of a length to accommodate bodily movement of the window sash assembly out of said frame and rotation about said vertical axis to a reversed position.

2. The combination of claim 1 including separable strut means secured to an inside part of the window construction for maintaining the window sash assembly in spaced parallel relation to the inner face of said frame.

3. A reversible window construction comprising a frame adapted to be fixed in a window opening of a building; a window assembly with two vertically movable sashes and having lintel, sill and side jambs fitting within said frame in sliding relation; and separate linkage means pivotally connected to said frame at respective inner portions and with said lintel and sill respectively at points on a common central vertical axis, said separate linkage means each being of a length to accommodate bodily movement of the window sash assembly out of said frame and rotation about said vertical axis to a reversed position; and removable locking means extending from the bottom portion of said frame and through said sill for holding the window sash assembly within the frame, said locking means being covered by the innermost sash in its closed position.

4. A reversible window construction comprising a frame adapted to be fixed in a window opening of a building; a window sash assembly having lintel, sill and side jambs fitted within said frame; separate linkage means pivotally connected to said frame at opposite inner portions and with said lintel and sill respectively at points on a common central vertical axis, said separate linkage means each being of a length to accommodate bodily movement of the window sash assembly out of said frame and rotation about said vertical axis to a reversed position; separable strut means secured to an inside part of the window construction for maintaining the window sash assembly in spaced parallel relation to the inner face of said frame; and removable locking means extending from the bottom portion of said frame and through said sill for holding the window sash assembly within the frame.

5. A reversible window construction comprising a frame adapted to be fixed in a window opening of a building; a bodily movable window sash assembly having lintel, sill and side jambs fitted within one side of said frame in sliding relation; a first horizontal trim member pivotally connected to the center of the top of the lintel for relative rotation about a vertical axis; linkage pivotally connected by one end to the inside of the frame and having a pivotal, supporting connection with the inner face of the first trim member; a second horizontal trim member pivotally connected to the center of the bottom of the sill for relative rotation about the same vertical axis; and linkage pivotally connected to the inside of the frame by one end and having a pivotal, supporting connection with the inner face of the second trim member, said linkages being connected at opposite sides of the frame.

6. A reversible window construction comprising a rectangular frame having upper, lower and upright framing members adapted to be fixed in a window opening of a building and arranged to cover the wall portions defining said opening; a bodily movable window assembly having lintel, sill and side jambs fitting within said frame in sliding relation, the portion of said frame extending about the opening thereof being provided with stripping engaging and sealing the inner sides of the lintel, side jambs and sill when the window assembly is in its innermost position within said frame; a first horizontal trim member pivotally connected with the center of said lintel for relative rotation about a vertical axis and disposed above said lintel for covering the adjacent portion of the upper framing member; a second horizontal trim member pivotally connected with the center of said sill for relative rotation about the same vertical axis and disposed below said sill for covering the adjacent portion of the lower framing member; and a horizontally extendible linkage for each of said trim members pivotally connected by one end to the inside of said frame and having a pivotal, supporting connection with the inner face of the respective trim member.

7. The combination of claim 6 in which said sill is formed to provide an inner wedge portion and said frame is formed with a wedge-shaped opening to receive the inner wedge portion of the sill when said drain ledge and sill are in engagement.

8. A reversible window construction comprising a rectangular frame having upper, lower and upright framing members adapted to be fixed in a window opening of a building and having outwardly extending portions for covering the wall portions defining said opening; a bodily movable window assembly with two balanced

vertically movable sashes and having lintel, sill and side jambs fitting within said frame in sliding relation, the portion of said frame extending about the opening thereof being provided with stripping engaging and sealing the inner sides of the lintel and side jambs, and with a strip member complementally engaging and sealing the adjacent edge of the sill, when the window assembly is in its innermost position within said frame; a first horizontal trim member pivotally connected with the center of said lintel for relative rotation about a vertical axis and disposed above said lintel for covering the adjacent portion of the upper framing member; a second horizontal trim member pivotally connected with the center of said sill for relative rotation about the same vertical axis and disposed below said sill for covering the adjacent portion of the lower framing member; a horizontally extendible linkage for each of said trim members pivotally connected by one end to the inside of said frame and having a pivotal, supporting connection with the inner face of the respective trim member; strut means secured to the inside of the said frame and connectible with said window assembly for maintaining said window assembly in spaced parallel relation to the inner face of said frame when said linkages are extended; and a removable bolt means passing through said lintel and into said lower framing member for holding the window sash assembly within the frame in sealing engagement therewith.
